UNITED STATES PATENT OFFICE.

JOSEPH C. SANDERS, OF ST. LOUIS, MISSOURI, ASSIGNOR TO AMERICAN FOUNDRY & MANUFACTURING CO., OF ST. LOUIS, MISSOURI, A CORPORATION OF MISSOURI.

FLOOR DRAIN.

Application filed January 2, 1926. Serial No. 78,835.

This invention relates to floor drains of the type that comprise a stationary member imbedded in the floor below the top surface of the floor and having a drain pipe connected to same, a vertically adjustable head piece carried by said drain pipe member and provided at its upper end with a grille or grating which extends flush or substantially so with the top surface of the floor, and a flashing formed 5 usually by a sheet of lead or other suitable water-proof element imbedded in the floor below the top surface of same and connected to said drain pipe member in such a manner as to intercept and collect any water which 10 seeps down around the exterior of the head piece of the drain.

The main object of my invention is to provide a floor drain of the general type referred to, which is of such construction that the stationary member of the drain and the water-proof element that co-operates with said member can be combined quickly and easily in such a manner as to eliminate the possibility of seepage finding its way into the foundation 25 layer of the floor in which said stationary member is imbedded.

The figure of the drawing is a vertical sectional view of a floor drain constructed in accordance with my invention.

Referring to the drawing which illustrates the preferred form of my invention, A designates the stationary member of the drain which may consist of a trap or a straight tubular member to which a drain pipe B is attached, x designates the foundation layer of the floor in which the member A is imbedded, y designates the finishing coat or top layer of the floor, C designates a water-proof element formed usually from a thin sheet of lead that 35 is arranged horizontally between the foundation layer x and top layer y of the floor adjacent the upper end of the member A, and D designates the vertically-adjustable head piece of the drain which is provided at its upper end with a grille or grating 1 that extends flush or substantially so with the top surface 40 of the floor.

In structures of the character referred to it is essential that the water-proof element C be 50 connected with the stationary member A of the drain in such a manner that any seepage which collects on the element C cannot escape into the foundation layer x of the floor, and in order to be successful from a commercial 55 standpoint, the drain must be constructed in

such a manner that the water-proof element C can be combined with the member A quickly and easily. Accordingly, I have provided the stationary member A of the drain with a clamping ring E that serves as a support for 60 the head piece D of the drain and which is adapted to be manipulated so as to clamp the water-proof element C tightly against a portion at the upper end of the stationary member A, herein illustrated as a laterally-projecting flange 2. The clamping ring E is preferably screwed into an internally-screw-threaded portion at the upper end of the member A, and said ring is provided with a laterally-projecting flange 3 that laps over 65 the water-proof element C and forces said element downwardly against the upper end of the member E when said ring is tightened by screwing it down into the member A. It is immaterial, so far as my broad idea is concerned, how the head piece D of the drain is supported on the clamping ring E, but I prefer to provide said head piece at its lower end with an externally screw-threaded portion 4 that is adapted to be screwed into internal 70 screw threads on said clamping ring. To facilitate screwing the clamping ring E into and out of the stationary member A of the drain, said ring E is provided on its top side with lugs 5 which are adapted to be engaged by a 75 bar or tool that is arranged crosswise of said ring when the head piece D of the drain is not positioned in said ring.

In installing the drain the stationary member A is first imbedded in the foundation layer 90 of the floor and a piece of sheet lead C or other water-proof material is then placed over the upper end of said member A and pressed downwardly slightly into the internally 95 screw-threaded opening in the upper end of said member, so as to mark the element C at the point where a portion of said element has to be removed to form a hole for the clamping ring E. After this portion of the element C has been cut out said element is again arranged horizontally on the flange 2 at the upper end of the stationary member A and the clamping ring E is then screwed into said member A, so as to cause the flange 3 on said ring to clamp the element C tightly against 105 the upper end of the member A. The flange 3 of the clamping ring E is then connected to the water-proof element C by a soldered joint 6, so as to eliminate the possibility of any water which collects on the element C seeping 110

- through the joint between said element and the flange 3 of the clamping ring and eventually working down into the foundation layer of the floor. Preferably, the peripheral edge of the flange 3 on the clamping ring E is beveled so as to permit the water-proof element C to be connected to said flange quickly and easily, simply by running a soldering iron around the beveled edge on said flange.
- 10 After the head piece D of the drain has been screwed into the clamping ring E, the top layer or finishing coating of the floor is applied, thus completely concealing the water-proof element C and encasing all of the head piece D of the drain, except the top edge of same and the grille 1 that is mounted in said head piece.
- 15 A floor drain of the construction above described effectively prevents water from seeping down into or through the foundation layer of the floor, and it is inexpensive to manufacture and easy to install.

Having thus described my invention, what

I claim as new and desire to secure by Letters Patent is:

A floor drain, comprising a member that is adapted to be imbedded in a floor below the top surface of same, a laterally-projecting flange at the upper end of said member, a water-proof element supported by said flange, 30 a clamping ring arranged in overlapping relation with said water-proof element and provided at its inner edge with a depending, externally-screw-threaded portion that is screwed into said member, a beveled surface 35 at the peripheral edge of the portion of said ring which laps over the water-proof element, adapted to be connected to said water-proof element by a soldered joint, upwardly-projecting lugs on the top side of said ring adapted to be engaged by a device arranged transversely of the ring that is being used to screw the ring into said member, and a vertically-adjustable head piece mounted in said clamping ring.
